J. F. AUER,
DEVICE FOR PRODUCING PAPER WRAPPING CORD,
APPLICATION FILED MAR. 16, 1916.

1,219,421.

Patented Mar. 20, 1917.

UNITED STATES PATENT OFFICE.

JOHN F. AUER, OF PHILADELPHIA, PENNSYLVANIA, ASSIGNOR TO AUER & TWITCHELL,
INC., OF DOVER, DELAWARE, A CORPORATION OF DELAWARE.

DEVICE FOR PRODUCING PAPER WRAPPING-CORD.

1,219,421.

Specification of Letters Patent. Patented Mar. 20, 1917.

Application filed March 16, 1916. Serial No. 84,544.

To all whom it may concern:

Be it known that I, JOHN F. AUER, a citizen of the United States, residing at the city of Philadelphia, in the county of Philadelphia and State of Pennsylvania, have invented certain new and useful Improvements in Devices for Producing Paper Wrapping-Cord, of which the following is a specification.

10 My invention relates to a holder for ribbon or fillet-like tough tissue paper in a roll and the device provided with a forming nozzle through which the ribbon or fillet of tissue paper is manually drawn to become 15 instantly an infolded, crinkled or crimped wrapping cord.

The nature, object and scope of my present invention will be more fully understood from the following description taken in connection with the accompanying drawings forming part hereof, in which—

20 Figure 1, is a view partly in section and partly in elevation, showing the internal constructive arrangement of the device as 25 embodying the essential main features of my invention, for producing infolded crinkled or crimped wrapping cord for various uses.

Fig. 2, is a vertical sectional view on the 30 line x, x , of Fig. 1, showing the detail arrangement of the contracted forming nozzle and through which instantly a narrow ribbon or fillet of tough tissue paper is transformed into an infolded crinkled or crimped 35 wrapping cord.

Fig. 3, is a vertical sectional view of a modified form of the device, showing two reels of narrow ribbon or fillet like tissue paper mounted thereon and also the forming nozzle for crinkling or crimping the two ribbons of tissue paper into the required crinkled or crimped wrapping cord; and

Fig. 4, is a longitudinal sectional view on the line y, y , of Fig. 3.

Referring to the drawings a , is a holder, as illustrated, in the form of a shield having a slidible cover-plate a^1 . In the lower portion of the holder is provided a forming

nozzle a^3 , the upper end of which is formed into coils a^4 , with bent guides a^5 , a^6 , forming ways for the infolding from the sides of the tissue paper ribbon or fillet c coming from the support or reel of Fig. 1 or 2, so that as it enters the forming nozzle a^3 , in its infolded condition it is therein 55 transformed into a crinkled or crimped condition as a wrapping cord for instant use.

The support or reel, for the paper web and on which it is mounted, consists of a drum or solid block b , arranged on a stud 60 or pin b^1 , fitted to the rear wall of the holder a , and projecting therefrom, as clearly shown in Figs. 1, 2 and 3. The paper web in coiled form is provided with an inner ring a^1 , as clearly shown in Fig. 2, and 65 which ring is arranged so as to lightly bear by friction against the drum or block b , but only sufficiently to permit of ready unwinding of the paper fillet or ribbon c , therefrom by a drawing action of the fillet or 70 ribbon to and through the infolding forming nozzle a^3 .

In Figs. 3 and 4, the holder for the narrow fillet or ribbon of tough texture tissue paper, is held on two reels, as shown, and the fillets or ribbons lead therefrom to and through the forming nozzle a^3 , as in Figs. 1 and 2. The guides above the nozzle proper are the same as in Figs. 1 and 2, except that two narrow strips or fillets of paper are 80 joined by infolding to become united to each other by the manual drawing operation of the same through the said forming nozzle a^3 , to cause instantly the same to be formed into the required wrapping cord, for tying 85 candy boxes or other packages. Tinted or colored tissue paper stock it will be apparent may be employed for giving the resultant product and to make in appearance 90 an attractive wrapping cord.

Having thus described the nature and object of my invention, what I claim as new and desire to secure by Letters Patent is:—

A holder provided with a forming nozzle and a support for a paper web mounted 95 thereon, said nozzle formed into coils and

having guides arranged adjacent to the mouth thereof for the infolding of the paper ribbon or fillet from said support, whereby the paper entering the nozzle in an infolded condition is transformed into a crimped condition, substantially and for the purposes described.

In witness whereof, I have hereunto set my signature in the presence of two subscribing witnesses.

JOHN F. AUER.
